UNITED STATES PATENT OFFICE.

JAMES F. WHEELER, OF GRAND VALLEY, COLORADO, ASSIGNOR OF ONE-THIRD TO ALFRED T. COOLEY AND ONE-THIRD TO JUDSON E. SIPPRELLE, BOTH OF GRAND VALLEY, COLORADO.

FASTENING DEVICE FOR MILK-CAN COVERS.

Application filed July 29, 1925. Serial No. 46,833.

This invention relates to an improvement in fastening devices for milk can covers, and aims to provide a device of this character which securely holds the cover in position and yet is readily releasable and also readily adjusted to locking position.

Another object of the invention resides in the provision of a device of this character which is permanently attached to the can 10 and cover, but which permits the cover to be manipulated to fill and discharge the can and which also permits the escape of dangerous pressures.

A further object is to provide a fastening 15 device of this character wherein slack and wear are automatically taken up.

A still further object is to provide a device of this character which is of simple and durable construction, reliable and effective 20 in operation, not liable to get out of order or to be broken, and easy and comparatively inexpensive to manufacture.

Other objects and advantages reside in certain novel features of the construction, 25 arrangement and combination of parts which will be hereinafter more fully described and particularly pointed out in the appended claims, reference being had to the accompanying drawing forming a part of 30 this specification, and in which:

Figure 1 is a view in perspective showing the fastening device in position to lock the cover to the can,

Figure 2 is a similar view showing the 35 fastening device released,

Figure 3 is a fragmentary plan view of the device, as shown in Figure 1, and

Figure 4 is a view of the fastening device 40 detached.

Referring to the drawing, the numeral 1 designates a milk can having a neck 2 provided with a flange 3. A cover 4 is provided and has a peripheral flange 5 engaging the flange 3 when the cover is applied to 45 the can. The flanges 3 and 5 have pairs of openings registrable when the cover is applied. The members of the pairs of openings are diametrically opposed.

The fastening device which constitutes 50 the present invention comprises a rod 10 constructed of metal sufficiently bendable and resilient to enable the rod to be shaped and formed as hereinafter described, but

which is substantially rigid when finally shaped. The rod is inserted through the 55 registering opening at one side, and has a washer 11 placed thereon to engage the flange 5 of the cover and a washer 12 placed thereon to engage the flange 3 of the can.

Adjacent its upper end the rod is curved laterally as at 13, and then formed with an open and almost a complete coil 14 which extends spiral fashion about and just beyond the adjacent portion of the rod 10. At its 60 lower end the rod is formed with an eye 15.

A retractile coil spring 16 is provided, and has one end connected as at 17 to the eye 15, and its other end connected to a hook 70 designated generally at 18. The hook 18 comprises a shank 19 having a loop 20 connected to the spring 16 and a bill 21 engageable with the other set of registering openings in the flanges of the can and cover.

The device may be assembled with the can 75 and cover by threading the coil 14 of the rod 10 upwardly through one set of openings prior to assembling the washer 11 thereon. The washer 11 is then placed on the rod 80 below the coil 14 and the coil 14 is flattened out to permanently connect the rod to the can and cover. The curved portion 13 permits the escape of gases that sometimes develop in the can as a result of fermentation. The cover can be lifted off of the can 85 and rotated away from the same unless the spring 16 is stretched around the neck of the can beneath the flanges and the bill of the hook 18 engaged with the other set of openings.

I claim:—

1. A fastening device for securing covers to milk cans comprising a rod connected to the can and cover, a spring connected to the rod, and a hook carried by the spring 95 and engageable with the can and cover at a point spaced from the rod.

2. A fastening device for securing a cover to a milk can comprising means for permanently connecting the can and cover while permitting the cover to be moved away from and rotated relative to the can, an elastic element having one end connected to said means and adapted to be stretched around the neck of the can below the cover, and 100 means for releasably connecting the other 105

end of the elastic element to the can and cover at a point spaced from said first mentioned means.

3. A fastening device for securing covers to milk cans comprising a rod permanently connected to the can and cover while permitting the cover to be moved away from and rotated relative to the can, a retractile coil spring connected to the rod and adapted to be stretched around the can below the cover, and a hook carried by the spring and engageable with the can and cover at a point spaced from the rod.

4. A fastening device for securing covers having apertured flanges to milk cans having necks provided with apertured flanges and comprising a rod inserted through one set of aligned apertures and having an offset coil at one end and an eye at its other end, a retractile coil spring having one end connected to the eye, and a hook carried by the other end of the coil spring, said hook being engageable with another set of registered openings when the spring is stretched around the neck of the can.

JAMES F. WHEELER.
